UNITED STATES PATENT OFFICE.

HENRY C. GUNDLACH, OF LA CROSSE, WISCONSIN.

CLOTH.

1,249,950.

Specification of Letters Patent. Patented Dec. 11, 1917.

Application filed April 1, 1916. Serial No. 88,337.

To all whom it may concern:

Be it known that I, HENRY C. GUNDLACH, a citizen of the United States, residing at La Crosse, in the county of La Crosse and 5 State of Wisconsin, have invented certain new and useful Improvements in Cloth, of which the following is a specification.

This invention relates to a cloth fabric of a novel weave and more particularly to a 10 cloth designed to be employed as a padding.

It is one aim of the invention to provide in a cloth fabric of the class mentioned a filler and warp and woof binding threads interwoven therewith in such manner that 15 the said binding threads will be located below the surfaces of the cloth and will, therefore, not be subjected to wear to the same degree as they would be if presented at the said surfaces of the cloth.

20 Another aim of the invention is to so bind the strands comprising the filler that the fabric will possess the desired strength and yet be sufficiently flexible and soft to adapt it to be used as a padding.

25 Another aim of the invention is to so weave the binding threads with each other and with the strands comprising the filler of the fabric that the said filler strands will not be liable to become displaced when the 30 cloth is subjected to strain.

In the accompanying drawings:

Figure 1 is a plan view of a piece of fabric woven in accordance with the present invention.

35 Fig. 2 is a fragmentary perspective view of a portion of the fabric.

Fig. 3 is a detail plan view of a portion thereof.

40 Fig. 4 is a sectional view substantially on the line 4—4 of Fig. 3.

In the drawings the filler is indicated in general by the numeral 1 and this filler may be of cotton, wool, artificial wool, or, in fact, any other material suitable for the purpose.

45 The filler comprises a number of strands of cotton or the like which are bound together by the binding threads of the fabric in a manner which will presently be explained, and each filler strand may comprise a num-

50 ber of filaments 2 laid side by side throughout the length of the strand or may comprise a single filament of suitable thickness or diameter. It will be understood, of course, that the number and size of the filaments comprising each strand or the thickness or diameter of the single filament, if

the strand comprises but a single filament, will depend upon the thickness which it is desired the finished fabric shall have.

In the drawings the woven binding for 60 the filler strands comprises warp threads 5 and woof threads 4, the warp threads 5 crossing and binding the filler strands at suitable intervals throughout the length of the strands and the woof threads 4 extending longitudinally between the strands. While any desired number of warp and 65 woof threads may be employed in weaving the fabric and for the purpose of binding the filler strands, in that embodiment of 70 the invention illustrated in the drawings, the warp comprises the threads 5, two of which are laid, in weaving the fabric across one side of the filler strand and two across the other side of the said filler strand, the 75 said threads 5 being brought together and interwoven with the woof threads 4 as indicated at 5, the threads 4 being preferably six in number and arranged in pairs as clearly shown in Fig. 2 of the drawings, 80 although it will be understood, as stated, that this number may be increased or decreased as found desirable and that the threads 5 and 4 may be of the same strength or, if desired, the threads 5 may possess 85 greater strength than the threads 4. It will be observed that the woof threads 4 extend longitudinally between the filler strands and lie substantially midway between the upper and under surfaces of the fabric and it will 90

also be apparent by reference to the drawings that the warp threads 5 are woven sufficiently tight to cause their portions which cross the filler strands to sink into the said filler strands and, therefore, occupy positions below the surfaces of the fabric so that they will be protected against wear and the fabric will be rendered more durable. Furthermore, by tightly weaving the warp threads 5 of the binding the filler strands 100 are more securely bound together and are positively prevented against slipping longitudinally through the warp.

This cloth is intended more particularly for covering the rollers of a mangle or other laundry machine for ironing or pressing linens. For such purpose, the cloth must be durable and must be resilient to avoid breaking buttons and damaging the linen; it must be capable of repelling dampness, and must 105 not ravel when cut to the desired length. The warp and woof threads in my cloth

are interwoven closely and the warp threads bind tightly around the fillers so that they are embedded therein on both surfaces of the fabric. As a result of this construction, the 5 surfaces of the cloth are corrugated both longitudinally and transversely and present the appearance of a repetition of well-defined rectangles having peaked central portions so that air spaces are provided to prevent 10 the padding from scorching under the constant heat from the cylinder. The form given the fabric, moreover, preserves its elasticity, resiliency or flexibility so that it will not pack tight and hard under the pressure to which it is subjected but will rebound 15 thereby maintaining the cushioning surface in proper condition and facilitating the escape of moisture and dampness while the machine is not in use.

20 Having thus described the invention, what is claimed as new is:

1. A woven fabric including relatively loose and soft filler strands, and means binding the said strands together, the said means comprising warp and woof threads relatively thin and tenacious, the said warp and woof threads each being arranged in groups and each group of the woof threads extending longitudinally between two of 25 the filler strands, the groups of warp threads being arranged at intervals in the lengths of 30

the filler strands and the said warp threads being interwoven with the groups of woof threads at points between the filler strands, each group of warp threads being divided 35 so that a part of the group will extend above and a part below the filler strands, adjacent ones of the filler strands being in mutual contact between the points of interweaving of the woof and warp threads and 40 the surfaces of the fabric being corrugated both longitudinally and transversely.

2. A woven fabric including relatively loose and soft filler strands, and means binding the strands together comprising relatively thin and tenacious woof and warp binding threads, the woof threads being arranged in groups between the filler strands and the warp threads being arranged in groups at intervals in the lengths of the 45 filler strands with the members of each group crossing the said filler strands at opposite faces of the fabric, the warp threads being interwoven with the woof threads without mutual intertwisting and being 50 drawn relatively tight whereby to be embedded in the opposite surfaces of said filler strands whereby the surfaces of the fabric will present adjoining rectangles having 55 peaked centers.

In testimony whereof I affix my signature.
HENRY C. GUNDLACH. [L.s.]
